WIREDRAWING MACHINE

Robert C. Pierce, Niles, Mich., assignor to National Standard Company, Niles, Mich., a corporation of Michigan

Application June 26, 1937, Serial No. 150,476

12 Claims. ((Cl. 205—14)

This invention relates to wire-drawing machines, and is illustrated as embodied in an automatic machine for drawing the wire successively through a series of dies progressively diminishing in size.

An object of the invention is to provide a sensitively controllable machine, by individually varying the speed of motors directly driving capstans drawing the wire through the dies, in accordance with the movements of devices on the opposite sides of the corresponding dies and which maintain a back tension on the wire at each die to facilitate drawing the wire through it.

Various features of novelty relate to the construction and arrangement of a simple and reliable control means of this sort for the various motors for example by utilizing a sprocket chain or the like to connect the tension device to its weight and also to drive the speed-change connections and by providing adjustments for varying the speed change caused by a given movement of the tension device, to vary the sensitivity, and for shifting the range of speeds without changing the sensitivity.

Another feature of the invention relates to providing accurate control of the circulation of a cooling liquid to the dies, and to the capstans.

These and other objects and features of the invention, including various novel combinations of parts and desirable particular constructions, will be apparent from the following description of the illustrative embodiment shown in the accompanying drawings, in which:

Figure 1 is a front elevation with part of the superstructure broken away of a wire drawing machine embodying my novel improvements;

Figure 2 is a section on the line 2—2 of Figure 1 made on a slightly enlarged scale;

Figure 3 is a partial section on the line 3—3 of Figure 2 showing on a still further enlarged scale details of the motor speed control rheostat operating mechanism;

Figure 4 is a section on the line 4—4 of Figure 3; and

Figure 5 is a wiring diagram of the electrical control and power supply of the machine.

Referring now to the figures, there is illustrated a wire drawing machine embodying my novel improvements in which the wire is passed successively through three dies, although it is to be understood that my improvements could be applied to a machine employing any number of dies, more or less, as conditions indicate to be desirable.

Such a machine as is illustrated is called a

"three pass" machine and may be considered as consisting of three units mounted on an integral frame 10 which I prefer to build up of standard structural steel shapes and plates welded together to form suitable supports for the various mechanisms.

The frame 10 may be arranged to provide a lower platform 12 upon which are mounted three motors 14, 16 and 18, the motor 14 being a constant speed alternating current motor (e. g. a squirrel cage induction motor), and the motors 16 and 18 being variable speed alternating current motors, preferably phase wound rotor induction motors.

These motors drive three capstan wheels 22, 24 and 26 arranged in a horizontal line along the machine and in a vertical plane. The driving means between the motors and capstans preferably consists of multiple V-belts 28 driving pulleys 30 journaled in blocks on a second platform 32 provided by the frame 10, the pulleys 30 being connected by suitable gearing to drive the capstan wheels at the desired speed.

In the first two units of the illustrated machine this gearing comprises pinions 34 mounted on the same shafts with the pulleys 30, driving gears 36 on layshafts 38 carrying additional pinions 40 which drive large gears 42 secured on shafts 44 on which the capstan wheels are mounted. The shafts 44 are journaled in blocks 46 attached to the platform 32.

In the third unit, due to the fact that each capstan must run at an average higher speed than the preceding one, one set of gears, e. g., gear 36, its layshaft 38 and pinion 40, is eliminated and the pinion 34 drives the large gear 42 directly.

Each of the capstans has associated therewith a die holder 48, 50 and 52 respectively, each containing a die (not shown) positioned with its center in the line of a vertical tangent to the left hand side of the periphery of the respective capstan. The capstans rotate counterclockwise (as seen in Figure 1) so as to draw wire vertically downward through the dies. The die holders are each arranged, in a manner not concerned with the present invention, so as to be adjustable angularly about two axes disposed at right angles in a horizontal plane to permit alignment of the die.

Wire is fed to the die in holder 48 from a guide sheave 54 rotatably mounted on a fixed bracket 57 attached to the top of the frame 10 in such a position that the wire leaves the sheaves 54 in line with the die and capstan pe-

riphery. Suitable means for supplying wire to the guide sheave from a reel or the like are shown in my copending application Serial No. 68,856, filed March 14, 1936.

Wire passes from the capstan 22 to the capstan 24 and from the capstan 24 to the capstan 26 over guide sheaves 56 and 58 respectively rotatably mounted on slides 60 and 62 vertically movable on guides 64 and 66. These guides are, in one desirable arrangement, each formed of two cylindrical rods 68 secured at their lower ends in brackets 70 bolted to the top of the frame 10. The upper ends of each pair of the rods 68 are tied together by cast members 72 which are formed with spaced sockets for said upper ends connected by a horizontal flange. The slides 60 and 62 are disposed between the pairs of rods and are formed with lugs having opposite outwardly directed semi-circular grooves fitting around the rods.

In order to tension the wire as it enters the die, in the manner described and claimed in my previously mentioned copending application, sprocket chains 74 are secured to the top of each slide. These chains pass over pairs of sprockets 76 mounted on pivots at the front and rear ends of channel members 78, the front ends of which are secured to the flanges of the cast members 72 and which extend to the rear of the machine where they are supported by vertically disposed angle irons 80.

The chains pass downwardly from the rear sprockets 76 and have weights 82 suspended thereon, preferably in the same manner employed in the usual weighing scale, so that weight may be added or removed conveniently.

In the illustrative embodiment a sheet of light gage metal is formed parti-cylindrically and bolted to each leg of the angle irons 80 to form a housing 84 for the weights 82.

For a purpose to be described below, additional pairs of sprockets 76 are arranged generally below the first described pairs near the bottom of the machine and the chains 74 are continued from the bottoms of the weights 82 under these sprockets and up to the bottoms of the slides 60 and 62 to form closed circuits. Turnbuckles 83 are provided above the weights 82 to keep the chains tight.

Another guide pulley 85, swingably mounted on a slide 86, slidably in a guide 88, is positioned to receive wire from the capstan 26 and feed it under tension to a windup reel (not shown) as described in my above identified copending application. The movements of this slide are preferably utilized to control the speed of the windup reel.

For reasons of safety to both machine and operator, it is desirable to have a locking device on the slides 60, 62 and 86 to prevent them from being thrown to the top of their respective guides should the wire break. The novel locking devices which I have provided comprise brackets 238 bolted at the bottom of the front and rear faces of the slides and extending to one side past one 65 of the rods 68 to form bearings for shafts 240.

The central portions of the shafts 240, between the brackets 238 are formed eccentrically (see Figure 4) and have pivoted thereon shoes 242 provided with friction linings 244 adapted to contact the rods 68 when the shafts 240 are rotated. At the end of the shafts toward the front of the machine arms 246 are secured carrying at their ends small rollers or sheaves 248 adapted to contact the wire extending from the sheaves 54, 56, 75

58 or 85 as the case may be. At the other end of the shafts 240 are secured arms 250 having tension springs 252 tensioned between their ends and some fixed part of the slides. The springs tend to rotate the shafts 240 to apply the shoes 242 to the rods 68 and lock the slide but the sheaves 248 bearing against the wire prevent this unless the wire breaks.

An important feature of the invention resides 10 in the means for controlling the speed of the motors 16 and 18 so as to maintain the wire tight and pass it on through each unit as rapidly as it leaves the preceding one while at the same time giving it a constant back pull.

To accomplish this the two variable speed motors 16 and 18 are respectively provided with rheostats 90 and 92 of any standard type shown diagrammatically in Figure 5 as each comprising, in the case of a three phase motor, three sets of contact points 94 arranged in arcs of a common circle and tapping successive portions of three resistances 96. To one end of each of the resistances is connected one phase lead of the wound rotor of the respective motor, and a three armed contactor 98 pivoted on the center of the above mentioned common circle serves to connect the phase leads in Y, and upon rotation to simultaneously introduce or take out some of the resistances 96 in each phase.

It will be understood that in the actual rheostat the contacts are so closely arranged or the contactor arms are so broad that they engage the next contact before disengaging the first one so that the rotor circuits are closed at all times.

The rheostats 90 and 92 are mounted on the upper part of the machine frame just to the left (as seen in Fig. 1) of the guides 64 and 66 respectively. With specific reference to Figure 3, the rheostats are operated by levers 100 having one end secured to shafts 102 journaled in and passing through the covers of the rheostat boxes. Arms 104 are secured on the inner ends of the shafts 102 and carry at their free ends the ends of tension springs 106 having their other ends secured to second arms 108 freely journaled on the shafts 102.

The arms 108 are forked at their free ends to engage pins 110 secured to the rheostat contactors 98, thus permitting the covers of the rheostat boxes to be freely removed and replaced. Lugs 112 on the arms 104 engage shoulders 114 on the arms 108 so that movement of the levers 100 in a clockwise direction positively moves the contactors through engagement of the lugs 112 and shoulders 114 while movement in the other direction moves the contactors resiliently under the influence of the springs 106.

The arms 100 are forked at their free ends and have pivoted in the forks sleeves 116 in each of which is rotatably mounted one end of a push rod 118. The push rods are prevented from axial movement by hand wheels 120 and collars 122 pinned thereto at opposite ends of the sleeves.

The rods 118 extend downwardly and are threaded into blocks 124 pivoted on slides 126, slidably arranged in slots 128 in arms 130. Hand-wheels 132 secured to threaded stems 134 extending centrally along the slots 128 and threadedly engaging the slides 126, form means for adjusting the positions of the slides 126 to vary the effective lengths of the arms 130. Similarly the hand wheels 120 and the threaded connections between the rods 118 and the blocks 124 form means for adjusting the effective lengths of the rods 118.

The arms 130 are keyed to shafts 136 journalled in cast brackets 138 bolted to the brackets 70 of the respective guides 64 and 66. Worm wheels 140 are keyed to the shafts 136 and mesh with worms 142 secured to shafts 144 also journalled in the brackets 138.

The shafts 144 carry sprockets 146, each arranged in line with the center of the corresponding slide, and which are engaged by the lower parts of chains 74 previously described. To hold the chain in engagement with the sprockets 146 guide sprockets 148 are pivotally mounted on the brackets 138 so as to engage the other side of the chains 74. Due to the fact that the chains 74 are continuous they will move the sprockets 146 positively in either direction proportionally to movement of the slides.

An important feature of the machine relates to arrangements for cooling the dies and capstans, and particularly to a visible discharge means for the cooling water whereby the operator of the machine may check at a glance the proper functioning of the cooling equipment. This feature is more fully described and is claimed in a copending application Serial No. 234,086 filed October 10, 1938.

I prefer to run a water main 152 along the back of the machine at the level of the top of the frame 10. Valves 154 open from this main and admit water to tubes 156 which lead to special pipe fittings 158 in the rear ends of the shafts 44. The shafts 44 are drilled and provided with tubes (not shown) defining concentric inner and outer passages through the shafts, (as described in my above-identified copending application) and through the inner passages thus defined the water passes to the front ends of the shafts 44 and then through tubes 160 to peripheral water jackets 162 formed on the capstans. The water then circulates around the capstans in these jackets and out through tubes 164 to the outer passages in the shafts 44 (not shown) and back to the fittings 158 from which it passes through tubes 166 to my novel sight gages or visible discharge means.

These sight gages comprise cast iron receptacles 168 closed at the bottom and open at the top and provided with integral bridges or supporting members 170 arranged across their tops and spaced upwardly therefrom. These supporting members carry the ends of the tubes 166 and the tubes are arranged to discharge downwardly into the receptacles. Rods 172 provided with hand wheels extend from the stems of the valves 154 to the front of the machine to facilitate operation of the valves.

Water is also conducted from the main 152 through tubes 174 to the die-holders 48, 50 and 52. The die holders are formed with passages for the circulation of water therethrough to cool the dies. The water enters from the tubes 174 at the left of the die-holders as seen in Figure 1, petcocks 176 being provided to cut off or adjust the flow of water. After circulating through the die holders the water leaves through tubes 178 which also terminate on the bridges 170 of the respective receptacles 168 and discharge downwardly thereinto.

At the bottom of the receptacles 168 drain pipes 180 extend to the rear of the machine and downward to a large pipe 182 which conducts the discharged cooling water to a drain or sewer.

It will be appreciated that this novel arrangement enables the machine operator to assure himself, by a glance along the machine, that

cooling water is being properly circulated in every part of the machine.

The electrical control and power system of this machine is shown by the wiring diagram designated Figure 5 and the novel features thereof are described and claimed in the copending application Serial No. 165,621 filed September 25, 1937, by Richard Koontz. It is believed desirable to incorporate herein a brief description of this system.

It is preferable to mount a switch box 184 on the machine in any desired position such as that shown in Figure 1, containing, for a three pass machine, four automatic switches three of which, designated 186, 188, and 190 are single throw three pole switches operated respectively by solenoids 192, 194 and 196 and the fourth of which is a single throw 4 pole switch 198 operated by a solenoid 200.

Adjacent the first unit of the machine are positioned a jog button 202 for turning over the first unit separately, a start button 204 for starting the whole machine together and a stop button 206 for stopping the whole machine. Jog buttons 208 and 210 are provided adjacent the two succeeding units for turning them over individually.

A three phase power line 212 is conducted to the switch box 184 the three wires of which may be designated 1, 2 and 3. Each of these wires is divided three ways and connected to the contacts of the switches 186, 188 and 190.

The power lines from the motors 14, 16 and 18 are connected respectively to the poles of the switches 186, 188 and 190. Thus closing any of these switches starts the corresponding motor. The solenoids of all the switches have one terminal connected to phase wire 1. The other terminals are connected to leads 214, 216 and 218, each of which divide into parallel circuits 219 and 220, 222 and 224, 226 and 228 respectively. Circuits 219, 222 and 224 are respectively connected to one contact of the push buttons 202, 208, and 210. The other contacts of these push buttons are connected to lead 2 of the power line by a wire 229 which also connects all four contacts of the switch 198 to lead 2. Circuits 220, 224 and 228 are each connected to a pole of the switch 198.

Solenoid 200 is also connected to phase lead 1 and its other terminal is connected to a line 230 which extends to one contact of the start button 204 the other contact being connected through wire 229 to lead 2. Shunted around the start button 204 is a circuit 232 containing the stop button 206 and a series of limit switches 234. The circuit 232 is connected to the remaining pole of the switch 198. It should be noted that the jog and start buttons are make switches and the stop button and limit switches are break switches.

The limit switches are placed in many positions around the machine and arranged to be operated by many contingencies such as wire breakage, tangling etc. An example is the placing of these switches, as seen in Fig. 2, at the top and bottom of the guides 62, 64 and 66 to be operated by cams 236 carried by the slides 58, 60 and 62 when and if the slides ever reach the limits of their movement.

The operation of the machine is as follows. In threading the machine it is desirable to operate any one of the motors 14, 16 or 18 individually. This is done by pushing and holding the respective jog button 202, 208 or 210 positioned by that motor to energize the solenoid 192, 194

and 196 to close the respective switch 186, 188, or 190. Upon releasing the button the motor stops. With the machine threaded, the start button 204 is pushed energizing the solenoid 200 and closing the switch 198. This in turn energizes all of the solenoids 192, 194 and 196 and closes all the switches 186, 188 and 190 to start all the motors simultaneously.

The circuit 232 is closed by the switch 198 to constitute a holding circuit for that switch so that the motors continue to run upon release of the start button. But upon opening circuit 232 by pushing the stop button 206 or any of the limit switches all the motors stop.

With the machine running, if the capstan 24 is turning too slow to take up all the wire leaving the capstan 22 the slide 60 moves up along the guide 64 under the influence of the weights 82. The incidental movement of the chain 74 rotates the sprocket 146 and worm 144, turning the arm 130 counterclockwise as seen in Figure 3 and swinging the arm 100 in the opposite direction through the pushrod 118 and thereby operating the rheostat 90 to reduce the amount of the resistances 96 in the rotor circuit. The speed of the motor 16 then increases until upon reaching a properly proportioned speed, the slide 62 is brought to rest. The same cycle occurs in the opposite direction should the speed be too high and also in each succeeding unit. This keeps the desired constant back pull on the wire as it passes through the successive dies in spite of the elongation of the wire in each die.

The two adjustments provided by handwheels 120 and 132 are important. Wheel 132 adjusts the lever arm of the lever 130 thereby changing the proportion between the movements of the slides and the corresponding movements of the rheostat. Thus the machine is made more or less sensitive as required for the particular type and size of wire being drawn. Handwheels 120 change the positions of the rheostats without changing the position of the slides and vice versa. With this provision full slide movement need not provide the full range of motor speed adjustment, but a narrower range may be selected sufficient to make all adjustments for the particular wire being drawn and thus the machine may be made more sensitive without limiting its versatility.

I claim:

1. A wire-drawing machine comprising a die, a capstan for drawing the wire vertically downward through the die, a motor for driving said capstan, means engaging the wire on the opposite side of the die from the drawing means and maintaining a substantially uniform back tension on the wire to facilitate drawing it through the die, said back tension means including a vertically-movable part whose vertical position is varied by variations in the feeding of the wire through the die, a device for controlling the speed of the motor, and connections from said part to said device for varying the motor speed to compensate for said variations.

2. A wire-drawing machine comprising a die, a capstan for drawing the wire vertically downward through the die, a motor for driving said capstan, means engaging the wire on the opposite side of the die from the drawing means and maintaining a substantially uniform back tension on the wire to facilitate drawing it through the die, said back tension means including a vertically-movable part whose vertical position is varied by variations in the feeding of the wire

through the die, a device for controlling the speed of the motor, a continuous sprocket chain operatively connected to and driven by said part, and operating connections for said device having a drive member meshing with and driven by said sprocket chain.

3. A control device for a wire-drawing machine or the like comprising spaced parallel vertical bars, a slide between said bars having parts guidingly engaging said bars, a brake member mounted on said slide and engageable with one of said bars, a lever pivoted on said slide and connected to operate said member, a spring urging said lever in a direction to cause the brake member to engage its bar, and a part carried by said lever and over which the wire being drawn in the machine passes and which is so arranged that the tension of the wire overcomes said spring and withdraws the brake member from its bar.

4. A wire-drawing machine or the like comprising, in combination with means for operating on the wire and with means for feeding the wire therethrough and with speed-varying means for the feeding means, vertically-arranged guide members having a slide movably mounted thereon, a brake member carried by the slide and having a spring urging it against one of the guide members and a part over which the wire passes and which is so connected that the tension of the wire overcomes the spring and withdraws the brake member from the guide member, means yieldingly urging the slide vertically of said guide members, a part carried by said slide and over which the wire passes in such a direction that the tension of the wire resists and is balanced against the yielding means, and connections from the slide to said speed varying means for operating it.

5. A wire-drawing machine or the like comprising, in combination with means for operating on the wire and with means for feeding the wire therethrough including a motor and means for varying the speed of the motor, vertically-arranged guide members having a slide movably mounted thereon, a safety device carried by the slide and which is urged by a spring in a direction to prevent movement of the slide and which has a part over which the wire passes and which is so connected that the tension of the wire overcomes the spring and holds the safety device inoperative, means yieldingly urging the slide vertically of said guide members, a part carried by said slide and over which the wire passes in such a direction that the tension of the wire resists and is balanced against the yielding means, and connections from the slide to said motor-speed varying means for operating it.

6. A wire-drawing machine or the like comprising, in combination with means for operating on the wire and with wire-feeding means including a speed-varying device, a part over which the wire passes, means yieldingly urging said part in a direction to create a back tension in the wire, a lever rocked by motion of said part, and a connection between said lever and the speed-varying device, said connection being readily adjustable as to length for varying the range of speeds without affecting the amount of speed variation caused by a given movement of the lever, said connection being in the form of a tie-rod, and the means for making the adjustment comprising a handwheel secured to the rod and means on one of the connected elements rotatably receiving one of the rod ends and means on

the other of the connected elements threadedly receiving the other end of the rod.

7. A wire-drawing machine or the like comprising, in combination with means for operating on the wire and with wire-feeding means including a speed-varying device, a part over which the wire passes, means yieldingly urging said part in a direction to create a back tension in the wire, a lever rocked by motion of said part, and a connection between said lever and the speed-varying device, said connection being readily adjustable as to length for varying the range of speeds without affecting the amount of speed variation caused by a given movement of the lever, said lever having its effective length readily adjustable to change the speed variation caused by a given lever movement without changing the range of speeds controlled by the lever.

8. A wire-drawing machine or the like comprising, in combination with means for operating on the wire and with wire-feeding means including a speed-varying device, a part over which the wire passes, means yieldingly urging said part in a direction to create a back tension in the wire, a lever rocked by motion of said part, and a connection between said lever and the speed-varying device, said lever having its effective length readily adjustable to change the speed variation caused by a given lever movement without changing the range of speeds controlled by the lever.

9. A wire-drawing machine comprising a series of dies, a corresponding series of capstans driven about parallel horizontal axes and which are all arranged in the same vertical plane and each of which is tangent to the wire below one of the dies and which draw the wire vertically downward through the dies, a part engaging the wire on the other side of the die from each capstan and over which the wire is looped to pass downwardly into the die, means yieldingly urging said parts individually upward to maintain a back tension on the wire at each die, a motor driving each capstan, and a speed-varying device for 45

each motor connected to be controlled by the one of said parts which is on the opposite side of the corresponding die.

10. A wire-drawing machine comprising a series of dies, a corresponding series of capstans driven about parallel horizontal axes and which are all arranged in the same vertical plane and each of which is tangent to the wire below one of the dies and which draw the wire vertically downward through the dies, spaced parallel vertical guide members adjacent each die, a slide on each set of guide members, a part on each slide engaging the wire on the other side of the die from the corresponding capstan and over which the wire is looped to pass downwardly into the die, means yieldingly urging each of said slides upward to maintain a back tension on the wire at each die, and a motor driving each capstan and provided with a motor speed-varying device connected to be controlled by the one of said slides which is on the opposite side of the corresponding die.

11. A control device for a wire-drawing machine or the like, comprising a guide, a slide movable on the guide, a brake member mounted on the slide and engageable with the guide, a lever pivoted on said slide and connected to operate said member, a spring urging said lever in a direction to cause the brake member to engage the guide, and a part carried by said lever and over which the wire being drawn in the machine passes and which is so arranged that the tension of the wire overcomes said spring and withdraws the brake member from the guide.

12. A control device for a wire-drawing machine or the like comprising a guide, a slide movable on said guide, a part carried by the slide over which the wire passes, means yieldably urging the slide in a direction to tension the wire, a brake member mounted on the slide and engageable with the guide and actuatable to resist said means and lock the slide on the guide when there is no wire passing over said part.

ROBERT C. PIERCE.
